SURGICAL MALLET

Joseph J. Neff, Los Altos, and Frank I. Fuller,
Palo Alto, Calif.

Application February 17, 1948, Serial No. 8,977

6 Claims. (Cl. 32—53)

1

This invention relates generally to surgical mallets such as are used for dental and bone surgery.

In the past it has been proposed to use electrically energized surgical mallets or impactors to take the place of the conventional manual type mallet and surgical tool. Insofar as applicant can determine such electrical surgical mallets have not been satisfactory and have not been used in practice to any substantial extent. This is attributed to a number of inherent disadvantages. For example the prior devices have not afforded sufficient flexibility of control over the impacts or blows applied to the tool. In addition they have relied upon electrical contacts for making and breaking an electrical energizing circuit. Such contacts are unreliable and make it difficult to secure proper control over both the intensity and frequency of the impacts applied.

In general it is an object of the present invention to provide a surgical mallet of the electrical type which will be highly practical and convenient to the operator, and which in general will avoid the disadvantages of prior electrical mallets.

An additional object of the invention is to provide a surgical mallet which avoids the use of electrical contacts for making and breaking an electrical energizing circuit.

A further object of the invention is to provide a device of the above character which is automatically inactive to apply impacts to the tool except when the operator is using the tool. In this connection the present device is characterized by an arrangement which retains the blow imparting member of the device inactive except during periods when the tool carried by the device is being pressed against the work.

Another object of the invention is to provide apparatus of the above character having electronic pulsing means for energizing the same.

Another object of the invention is to provide a novel type of electronic pulsing means which is adjustable as to frequency and intensity of the generated pulses.

Further objects of the invention will appear from the following description in which the preferred embodiment has been set forth in detail in conjunction with the accompanying drawing.

Referring to the drawing:

Figure 1 is a diagrammatic view illustrating apparatus incorporating the present invention.

Figure 2 is a side elevational view in section illustrating an electrical surgical mallet incorporating the present invention.

Figure 3 is a side elevational detail in section

2

illustrating certain parts of the device in a different operating position from that shown in Figure 2.

Figure 4 is a wave form curve illustrating the wave form of current supplied by the pulse generator.

Referring first to Figure 1 of the drawing, we have shown a device 10 constructed in accordance with our invention, and electrically connected to the pulse generating means 11. The pulse generating means is adapted to produce unidirectional electrical pulses recurrently, and at a frequency which can be adjusted or controlled by the operator. The device 10 is of such size and shape that it can be readily held in the hand of an operator and used in such operations as dental surgery, bone surgery or the like.

The device 10 as illustrated in Figure 2 comprises a body or housing 12 which is elongated as to form, and which serves to carry and enclose the working parts of the device. For convenience the body is made of a plurality of parts, including the end part 12a which has threaded engagement 13 with the cylindrical shell part 12b, and the tapered portion 12c which has a threaded connection 14 with the other end of part 12b.

Extending longitudinally within the shell part 12b, there is a sleeve 15 which is of non-magnetic material, and which has collars 16 and 17 mounted upon its ends. A magnetic winding or solenoid coil 18 is disposed about the sleeve 15. Sleeve 15 forms a longitudinally extending bore 19, within which the metal plunger 21 is slidably fitted. This plunger is formed of magnetic material such as steel, and forms a part of the magnetic field of the solenoid coil as will be presently explained.

Near the rear end of the device a liner 22 is fitted within the shell part 12b, and serves together with the closure disc 23 and collar 17, to form a terminal space 24 in which electrical connections can be made.

A flexible insulated electrical cord 26 extends through an opening 27 in the part 12a and the flexible tubular conductor 28 of this cord is grounded to the metal parts of the device by connection to the metal disc 23. The central conductor 31 of the cord extends into the space 24 and is electrically connected to the metal terminal pin 32. This terminal pin is mounted within an insulating bushing and is electrically connected to one terminal wire leading from the solenoid coil 18. The other terminal of the coil 18 is electrically grounded to the metal parts of

the device and is thus electrically connected to the conductor 28.

Mounted between the collar 17 and the closure disc 23, there is a metal block 33 which provides a stop shoulder 34 for engagement with the adjacent end of the plunger 21.

Adjacent the forward end of the solenoid coil 18, there is a member 36 which can be retained in place by threaded engagement 37 with the shell part 12b, as illustrated. Member 36 has a rearwardly extending portion 38 of annular cross section, which fits within the forward end of the sleeve 15. As will be presently explained the rear end face of portion 36 forms an abutment stop adapted to be engaged by the forward end of plunger 21. It is desirable in this connection to form the rear end face 39 of portion 38, and also the cooperating forward end face 41 of the plunger 21 substantially conical shaped as illustrated. Member 36, together with the shell part 12b and the collar 17, is likewise formed of magnetic material such as a suitable steel, to form together with the magnetic plunger 21 a field or magnetic flux path for the solenoid coil. It will be noted that the magnetic field is closed when the plunger 21 is moved downwardly into engagement with the portion 38, as illustrated in Figure 3.

The body part 12c of the device is provided with a bore 42 in alignment with the axis of the solenoid plunger 21, and the solenoid coil. A rigid rod 43 is slidably fitted in bore 42, and forms what can be termed an impact transmitting member. The forward end of member 43 is provided with a mounting 44 for a chisel or other type of tool 46. Mounting 44 can be of the collet type including a rotatable ferrule having threaded engagement 48 with the exterior end of the member 43. The end portion 49 is split and provided with a socket 51 for receiving the shank end of the tool.

In order to provide suitable means for preventing rotation of the member 43, its inner end is shown provided with a laterally extending pin 52, the ends of which are slidably accommodated within the slots 53. These slots are formed in a guide sleeve 54, which is mounted to or formed integral with the body part 12c.

Spring means is provided for urging the member 43 downwardly as viewed in Figure 2, and also for urging the solenoid plunger 21 upwardly. It is preferable to use a single coiled compression spring 56 as illustrated. This spring extends through the axial bore 57 formed in the member 36, with its one end seated upon the adjacent end of the member 43, and its other end seated upon an annular shoulder 58 formed within the plunger 21.

Means are provided whereby when the solenoid coil is energized to cause the plunger 21 to move downwardly as viewed in Figure 2, an impact or blow is imparted to the member 43 and thus transmitted to the tool 46. Thus a hardened steel pin 61 is mounted in the forward end of the plunger 21 and is adapted to strike the end of a hard metal pin or button 62 mounted upon or forming the end of the member 43.

The parts described above are proportioned whereby the member 43, together with the tool mounting 44 and the tool 46 has limited permissible sliding movement axially of the device and between what may be termed projected and retracted limiting positions. The forward limiting position is determined by engagement of the pin 52 with the ends of slot 53 (see Figure 2).

The retracted limiting position is determined by engagement of pin 52 with the end face 63 provided on the member 36. The first limiting position of the plunger 21 is as is illustrated in Figure 2, and is determined by engagement of the rear end face of the plunger with the shoulder 34. The second limiting position of plunger 21 is determined by engagement between the forward end of plunger 21, and the rear end of portion 38, or in other words by physical contact between the surfaces 39 and 41. Spring 56 serves to normally urge the plunger toward the first named limiting position, and also serves to urge the member 43 toward its projected position. When the plunger 21 is in its second limiting position (see Figure 3) the opposed ends of the pins 61 and 62 are in contact.

Various types of electrical pulse generators can be used with the device described above. The generator should supply unidirectional spaced recurrent pulses at a desired frequency, and it is desirable that the frequency be subject to adjustment at the will of the operator. Likewise it is desirable to permit adjustment of the intensity of the pulses, to thereby adjust the intensity of the impacts. The electronic type of pulse generator illustrated in Figure 1 has been found desirable and satisfactory. It consists of a suitable gas filled tube 66 having plate, control and cathode elements, as for example a tetrode thyratron of the type known by manufacturers' specifications as No. 2D21. The plate 67 of this tube is shown connected to the cathode 68 of a two-way rectifier tube 69. This tube can be one of the type known by manufacturers' specifications as 6X5. The two anodes 71 and 72 of rectifier tube 69 are connected to the terminals of the transformer secondary 73. The primary 74 of this transformer can connect with a standard 110 volt alternating current supply line. The cathode 76 of tube 66 is connected by conductor 77 to the midpoint of secondary winding 73, in series with the resistor 78. The screen grid 79 of the tube 66 is shown conductively connected to the cathode 76.

A resistance-capacitance circuit serves to time firing of the tube 66. This circuit includes the series resistors 82 and 83, connected between the conductor 77 and conductor 84. Resistors 82 and 83 are shunted by the condenser 86 and conductor 84 is connected to the transformer side of the resistor 78, through the resistor 87. Conductor 84 is also connected to the control grid 81 of tube 66, in series with the resistor 88. The output terminals 89 and 91 of the generator are connected respectively to the conductors 77 and 70, in series with the variable resistor 92 and charging condenser 93. Condenser 93 is shown shunted by a resistor 94. The current supply transformer can be provided with a supplemental secondary 95 for supplying current to the cathode heaters of the tubes 66 and 69.

In one particular example the values of the resistors and condensers used in the pulse generator were as follows:

Resistor 78	4000 ohms
Resistor 87	2.5 megohms
Fixed Resistor 82	0.3 megohms
Variable Resistor 83	From 0 to 1 megohm
Variable Resistor 92	From 0 to 500 ohms
Condenser 86	0.1 microfarad
Condenser 93	16 microfarads
Resistor 94	1 megohm

In the foregoing example the solenoid coil 18 for the device 10 consisted of 1800 turns of No. 31 enamel insulated copper wire, the coil measuring about 2 inches long and $\frac{3}{4}$ inch outside diameter with sleeve 15 having an inside diameter of about $\frac{3}{8}$ inch.

In practice the parts of the generator as described above are mounted in a suitable enclosing box, with two controls for manual adjustment. One control serves to vary the value of resistor 92 and the other varies resistor 83. Adjustment of resistor 92 varies the amplitude or intensity of the pulses applied to the device 10, and adjustment of resistor 83 varies the frequency of the pulses.

The generator described above is capable of supplying current having a wave form substantially as illustrated in Figure 4. It will be noted that the waveform is approximately saw-tooth, and that the pulses are spaced $\frac{1}{2}$ cycle apart. In a typical instance the frequency of the pulses can be adjusted between 20 to 60 cycles per minute. At the beginning of a charging cycle, following firing of tube 66, a high voltage drop is applied across condenser 93 to charge the same. During this time condenser 86, which has been charged during the preceding firing cycle, is discharging through resistors 82 and 83. After full charging of condenser 93, the voltage drop across condenser 86 falls to a sufficiently low value to fire the tube 66. Firing of tube 66 causes the plate-cathode impedance of the same to be reduced to a low value whereby condenser 93 discharges through the same to supply a current pulse to the output circuit. Discharging of condenser 93 causes simultaneous recharging of the timing condenser 86 whereby at the end of the discharging cycle the control grid of the tube 66 is biased sufficiently negative to again block current from the rectifier.

Operation of the apparatus described above is as follows: Assuming that the generator is in operation and that the frequency and amplitude of the pulses are adjusted to be of desired values, current pulses are supplied to the winding 18 of the solenoid at recurrent spaced intervals. Assuming that the device 10 is being held in the hand of the operator, but that the tool 46 is not being pressed against the work, the first current pulse received serves to move the magnetic plunger 21 forwardly to its limiting position, with the surfaces 39 and 41 in direct physical contact. Since the plunger 21 together with member 36 is made of ordinary steel, which will retain a substantial amount of residual magnetism during the intervals between pulses, the residual magnetism will serve to hold the plunger in a forward position as illustrated in Figure 3. Thus under such conditions the plunger does not reciprocate in response to the recurrent energization of the coil 18, and no blows are imparted to the member 43 or to the tool 46.

The operator now places the tool 46 against the work, which may be a tooth or other bone, and when it is desired to apply blows to the tool the operator presses against the work with sufficient force to cause the plunger to be forced rearwardly and separated from its magnetic attachment to the face 39. Immediately thereafter the plunger commences to reciprocate in response to the energizing pulsations. Thus when a pulse is received the plunger 21 is propelled forwardly to cause the pin 61 to strike a blow upon the pin 62, and thus apply an impact through the member 43 to the tool 46. Such impacts will continue as

long as some pressure is exerted by the operator against the work. Immediately upon removing the tool 46 from the work, or when the operator ceases to apply any further pressure against the work, the plunger 21 again magnetically adheres or sticks to the end face 39 and is thereby made inoperative.

Either before or during operation of the plunger to apply impacts to the tool, the operator may 10 adjust the pulse generator to vary the frequency of the pulses, or to vary the intensity of the blows. Adjustment of resistor 83 serves to vary the frequency of the blows over a substantial range, while adjustment of resistor 92 serves to 15 vary the amplitude or intensity of the blows.

In the foregoing description the pulse generator 11 is adjusted in such a manner that between pulses the current flow drops down to a relatively 20 low value. One relies entirely upon residual magnetism to hold the solenoid plunger 21 in forward inactive position. Generally, however, it is desirable to provide sufficient current flow between pulses to supplement the residual magnetism and thus aid in retaining the plunger in 25 its forward inactive position, without however interfering with normal reciprocation of the plunger. For the particular pulse generator described, holding current between pulses is provided by the charging current through condenser 93 supplemented by current flow through resistor 94, and current flow through resistance 94 by 30 itself when condenser 93 has been charged. Increased holding current can be provided by reducing the value of resistor 94.

In place of the pulse generator described above, various other types of electronic or gaseous tube generators can be used, which are capable of 35 supplying unidirectional pulses at regularly spaced time intervals. It is also possible to provide mechanical devices for this purpose, as for example pulse generators of the vibrating contact or rotary commutator type.

It will be evident from the foregoing that our 45 device has many inherent advantages. Electrical contacts within the device itself are totally eliminated. Blows or impacts are automatically applied when the operator applies pressure upon the work, and automatically cease when such 50 pressure is removed. The operator can adapt the device for a wide variety of work by adjusting the frequency of the pulses and their amplitude.

We claim:

1. In a surgical mallet, a housing adapted to 55 be held by an operator, an impact transmitting member slidably disposed within the housing, a tool mounting on one end of said member, an electrical solenoid coil carried by the housing, plunger means aligned with the impact transmitting member and movable within the solenoid coil to apply impacts to the impact transmitting member in response to current energization of the coil, and magnetic means for holding said plunger inactive when the operator fails to apply 60 force to a tool carried by said mounting.

2. A surgical mallet comprising a housing adapted to be held by an operator, an impact transmitting member slidably disposed within the housing, a tool mounting carried by the outer 70 end of said member, said thrust transmitting member being movable longitudinally of the handle between projected and retracted limiting positions, a solenoid coil carried by the housing and adapted to be energized by an independent source 75 of recurrent electrical pulses, a magnetic field

for said solenoid coil including a plunger of magnetic material disposed in alignment with said impact transmitting member, said plunger being adapted to move to apply blows to the impact transmitting member in response to recurrent energization of the solenoid coil, and magnetic means for retaining said solenoid inactive in response to energization of the coil with recurrent pulses, during periods when no force is being applied to a tool carried by said thrust transmitting member.

3. A surgical mallet as in claim 2 together with spring means serving to urge the impact transmitting member towards its projected position and serving to urge said plunger in a direction away from said impact transmitting member.

4. A surgical mallet as in claim 3 in which said spring means comprises a single spring having one end of the spring engaging said impact transmitting member and the other end of the same engaging said solenoid plunger.

5. In a surgical mallet adapted to apply recurrent blows to a surgical tool, a housing formed to provide a handle, a rigid impact transmitting member disposed within the handle and movable between limiting projected and retracted positions, a tool mounting on the exterior end of said member adapted to grip a surgical tool, a solenoid coil carried by the handle and adapted to be energized by an independent source of recurrent electrical pulses, a magnetic field for said solenoid coil including a plunger of magnetic material, said plunger being disposed within the coil and aligned with the impact transmitting

member, the plunger being slidable from a first limiting position to a second limiting position to apply an impact to said impact transmitting member, stop means for limiting movement of the plunger in a direction toward said impact transmitting member whereby movement of said plunger is confined between said first and second limiting positions, spring means serving to urge the impact transmitting member toward its projected position and serving to urge the plunger toward its first limiting position, said stop means including a member of magnetic material serving together with the magnetic material of the plunger to magnetically retain said plunger in said second limiting position when no pressure is being applied to a tool carried by the mounting.

6. A surgical mallet as in claim 5 in which said spring means is a single spring having one end of the same acting against said impact transmitting member and the other end of the same acting against said plunger.
